[57] CLAIM

The ornamental design for the knee pad, as shown and described.

DESCRIPTION

FIG. 1 is a front and right side perspective view of a kneepad showing my new design;

FIG. 2 is a right side view thereof;

FIG. 3 is a front view thereof;

FIG. 4 is a left side view thereof;

FIG. 5 is a back view thereof;

FIG. 6 is a top view thereof;

FIG. 7 is a bottom view thereof; and,

FIG. 8 is a front and left side perspective view thereof.

The leg shown in broken lines in FIGS. 1 and 8 is shown for illustrative purposes only and forms no part of the claimed design. The broken lines on the kneepad represent conventional stitching and the crosshatch shading is understood to repeat throughout the indicated area.
